the same time an abutment 36 extends upwardly from trip lever 23 arrests coin lever 27, holding it as shown in Fig. 3, upon completion of the weighing operation, the poises 23^a of the poise beam is in 90^a until, 100^a from the platform, lifting one end of lever 6 and pin 23^a, thrusting outer end of lever 6 and pin 23^a, 105^a upwardly. corresponding lowering of its end 23^a allows coin lever 27 to fall to the limit of its movement, as in Fig. 3, whereupon the coin will roll out into the receptacle 32. The end of arm 27 being thus lightened, 110^a its counterweighted other end 30 will fall, 110^a raising the coin pocket 26 back again to normal position, and again throwing arm 48 against friction rod 37, pressing it against holding abutment 49, so as to hold beam 8, 115^a ready for another operation. When provided with spring 17, the tension of the spring may be so adjusted that a weight, say, twenty pounds, on the scale, 115^a extends the spring, so that it is removed from the scale, 115^a and the beam 8 is caused to operate to its position. The coin ar-

It will thus be seen that for ordinary weighing operations, the additional co-acting controlling levers for the trip lever and the poise beam holding rod, hereinbefore described, are not necessarily required. For the purpose of preventing the coin from being removed from the scale, the total load on the scale platform will be adjusted so that if the spring is depressed from the end 23^a of trip lever 23, to release the coin, the spring will operate to depress end 23^a of trip lever 23, to release the coin.

115
the ten-
adjusted that a
weight, say ten to
on the scale, platform will
removed from the scale, the spring will
operate to depress end 23^a of trip lever 23, to
release the coin.
It will thus be seen that for ordinary
weighing operations, the additional co-act- 125

the noise beam holding rod, hereinafter de-
scribed, are not necessarily required.
For the purpose of preventing fraudulent
use of the machine, as double weighing

single coin, I have embodied mechanism operable in connection with the poise beam, a locking device therefor, and the trip lever, whereby the trip lever will also operate to 5 return to normal position, effecting discharge of the coin and upward movement of coin lever 27 and resulting in holding of the poise beam so as to prevent further action until the platform is entirely released from 10 the load, or another coin deposited.

Such mechanism consists of a pendant holding or friction rod 37 pivoted to the outer end of the poise beam at 38 and hanging vertically within the casing 5 at one end 15 thereof adjacent to the counterweighted ends of the coin lever and trip lever respectively. At the lower end of rod 37 is a pin 39 extending between an upper tilting lever 40 and a lower tilting lever 41, lever 40 being pivoted at 42 and lever 41 at 43 on suitable supporting standards.

Each of said tilting levers 40 and 41 is provided with a bifurcated terminal 44, 45, respectively, the divided arms of which 25 brace a lug 46 and 47 at the upper and lower portions of the counterweighted end of trip lever 23.

By this means, upon the scale being in 30 equipoise (Fig. 2), and an additional weight being applied to the platform, the long end of the poise beam will rise, lifting rod 37 and thrusting lever 40 upwardly, lifting rear end 23^b of lever 23 and lowering its end 23^a, discharging the coin and immediately 35 allowing the coin lever 27 to rise, and lock the beam.

Said lever 27 is provided at its counterweighted end with an arm 48 adapted to engage the edge of rod 37, and to thrust 40 its opposite edge over against an interlocking knife edge abutment 49 adapted to engage one of a series of teeth 50 on rod 37, or merely against the smooth edge of the rod. It will be understood that it is not necessary 45 to cause a positive interlock between abutment 49 and the rod 37, so that the teeth 50 may, if desired, be dispensed with, or so designed as to interpose the necessary frictional holding engagement. Thereupon the 50 machine will be held against further operation to register an additional weight until another coin has been deposited.

Likewise, should the first load, the weight 55 of which has been ascertained, be partially removed from the platform for the purpose of independently weighing a lighter or heavier load, the long end of the poise beam will be lowered, thrusting pin 39 against lever 41 beyond its fulcrum 43, thus tilting 60 upwardly the counterweighted end of trip lever 23 and lowering its other end 23^a, effecting discharge of the coin and the same result.

The trip lever thus performs a double 65 function.

When it is in weighing position, the scale being in balance, abutment 36 is sufficiently high to stop the coin lever before the coin reaches the lower edge of the guard 31, but when the trip lever is raised at the rear end 70 by variation of the load on the scale, the front end 23^a drops, the coin lever is depressed by the weight of the coin, following abutment 36 down, until the coin clears the guard 31 and rolls out into the receptacle, 75 releasing the lever, which returns to normal position.

The other function of the trip lever is through the coin holder, which, operating as described, rises after release of the coin, 80 and cooperates with the controlling holding rod 37.

It will be entirely clear from the foregoing description that the scale may be used with the spring 17 in connection with the 85 trip lever 23 and steelyard lever 6, dispensing with the levers 40 and 41 and pin 39. In such case, for ordinary weighing, the person to be weighed will step on the platform either before or after placing the coin in the 90 chute. When the coin is so placed, the person being on the platform, the poises can be moved until the scale is balanced and the weight has been ascertained.

In such arrangement, it is only necessary 95 to instruct the person to be weighed that he stand on the platform before dropping the coin, and in such case also the coin chute releasing lever 34—35 may be dispensed with.

When the party has been weighed and has stepped from the platform, the weight being released from lever 6, spring 17 raises end 23^b of trip lever 23, effecting discharge of the coin as described. With such form of 105 construction, without levers 40, 41, there is nothing to prevent one person from keeping all or part of his weight on the platform until a second person gets on the platform, who could then weigh himself the same as 110 the first.

When the levers 40, 41, and pin 39 of rod 37 are utilized, either without the spring 17, or in combination with it as shown, trip lever 23 will be positively actuated upon any 115 material variation of the weight on the platform, by movement of the beam 8 up or down, as described.

In such case, the instructions which may be conspicuously posted, should be that the 120 party to be weighed stand on the platform before dropping the coin in the chute. This being done, and knowing his weight approximately, as say 165 pounds, the poise 10 will be set to 150 pounds. Having placed 125 a coin in the chute, he will then adjust the upper poise 11 outwardly on its beam, and the scale, being within 50 pounds of balance or less, and the steelyard lever having lowered, the counter-weighted end of trip lever 130

23 will also fall. This moves arm 34-35 upwardly, allowing the coin to drop into the coin pocket 26, lowering lever 27 until it rests on abutment 36, as described.

5 The coin lever will thus be held in such position while the party is adjusting the poises to ascertain his weight.

The scale will remain free, because when the coin lever drops the arm 48 is retracted, 10 rod 37 will hang pendently free from friction abutment 49; pin 39 will be relieved from engagement with either lever 40 or 41, when the beam is balanced, ample clearance being provided so that the rod is free to move up and down without bearing against either of said elements.

When the party has balanced and ascertained his weight, he then steps from the scale, when the outer end of the poise beam 20 drops, and pin 39 drops on the end of lever 38 41 with considerable force, raising the other end of said lever as described, effecting discharge of the coin and resulting in the return of the coin lever to normal position.

25 By using this upper short lever 40 more than one person cannot be weighed. If a second person would attempt to get on the scale before the first one gets off, the additional weight would raise the outer end of 30 the poise beam also with considerable force, and if the poise beam was more than fifty pounds out of balance, the upward pressure on lever 40 would raise the rear end of the trip lever, discharging the coin. This is because more than 50 pounds out of balance are 35 necessary to render the lever 40 or 41 operative by action of pin 39.

It will be understood that while the scale is normally sensitive and accurate, the 40 controlling mechanism to effect discharge of the coin, either upon release of the load on the scale or by materially increasing the load, is only operable by a considerable pull on the beam, upwardly or downwardly.

45 Thus upon release of the weight or its material increase on the platform, throwing the scale out of balance, the pull or thrust of rod 37 and pin 39 will cause either lever 41 or 40 to be actuated with sufficient 50 force to operate the trip lever 23. This is because of the relative leverage values, the power of pin 39 acting on the short end of the levers, and they in turn acting on the short end of trip lever 23. These parts will 55 therefore not be affected by ordinary oscillating movements of the beam and of pin 39.

The clearance for terminal 8^a in trig loop 8^b is sufficient to permit sufficient movement of pin 39 to effect the desired result before 60 the beam comes to rest at either the top or bottom of the trig loop.

Thus it will be seen that the coin will be discharged when a single person gets off the scale, or when an additional person gets on.

65 In this form of construction, utilizing

lever 40, the advantage of combining the coin lever and pocket with the trip lever, as described, is in preventing the coin from dropping until the poises are moved almost to exact balance, otherwise if the coin would 70 drop when the scale is out of balance, the trip lever being lowered, would allow the coin to roll out before the weighing operation is completed.

By instructing that the poises be set at approximate balance before the coin is dropped in the coin chute and the party to be weighed on the platform, the use of the coin holder might be dispensed with.

What I claim is:

1. In a weighing machine, the combination with a poise beam and poise, and means connecting the beam with weighing mechanism, of a vertically movable stud connected with said means, a retracting spring 85 therefor, a trip lever, a poise beam holding device, and a movable member adapted to co-act with said holding device and said trip lever.

2. In a weighing machine, the combination with a poise beam and poise, and means connecting the beam with weighing mechanism, of a vertically movable stud connected with said means; a retracting spring therefor, a trip lever, a poise beam holding device, and a pivoted counterweighted lever adapted to be depressed by a temporary load adapted to co-act with said holding device and said lever.

3. In a weighing machine, the combination with a poise beam and poise, and means connecting the beam with weighing mechanism, of a vertically movable stud connected with said means, a retracting spring therefor, a trip lever, a poise beam locking device, 105 and a movable member adapted to co-act with said trip lever and having an arm adapted to engage the locking device.

4. In a coin controlled weighing machine, the combination with a poise beam having a 110 depending holding rod, of a trip lever; means whereby the trip lever varies its position dependent on the placing of a load on the weighing machine, and a pivoted holding and releasing lever operable by a coin 115 adapted to engage and disengage with said holding rod and trip lever respectively.

5. In a coin controlled weighing machine, the combination with a poise beam having a 120 depending holding rod, of a trip lever, a spring-retracted load-controlled device operable to tilt said lever when a load is placed on the machine, and a coin lever having an arm adapted to engage and deflect the holding rod and provided with a coin holder.

6. In a coin controlled weighing machine, the combination with a poise beam and weighing mechanism connected therewith, of a trip lever, a spring-retracted actuating device therefor dependent on the load on 130

- the machine, a coin chute, a coin arrester connected with the trip lever, a coin lever, and a poise beam holding device adapted to be engaged by the coin lever.
- 5 7. In a coin controlled weighing machine, the combination with a poise beam and weighing mechanism connected therewith, of a trip lever, a spring-retracted actuating device therefor dependent on the load on the 10 machine, a coin chute, a coin arrester connected with the trip lever, a coin lever, and a poise beam holding device adapted to be engaged by an arm of the coin lever and to be pressed into engagement with an arresting 15 element.
8. In a machine of the class described, the combination with the poise beam, of a pivoted trip lever having a coin lever support, means for elevating the trip lever during 20 weighing, a coin chute, a coin arresting arm operable across said chute, a holding rod depending from the poise beam, a holding abutment therefor, a pivoted coin lever having an arm for the holding rod and a coin 25 holder, said lever being adapted to engage the coin lever support.
9. In a machine of the class described, the combination with the poise beam, of a pivoted trip lever having a coin lever support, 30 means for elevating the trip lever during weighing, a coin chute, a coin arresting arm operable across said chute, a holding rod depending from the poise beam, a holding abutment therefor, a pivoted coin lever having 35 an arm for the locking rod and a coin holder, said coin lever being adapted to engage the coin lever support, and a coin retaining guard extending throughout a portion of the path of movement of the coin 40 lever and holder.
10. In a machine of the class described, the combination with the poise beam, of a pivoted trip lever having a coin lever support, a spring-retracted load-actuated stud 45 operable to tilt said lever, supplemental levers engaging the trip lever, a holding rod depending from the poise beam provided with a terminal pin adapted to engage said levers and actuate the trip lever, a holding 50 abutment for said holding rod, a coin chute, a coin arresting arm extending from the trip lever, and a coin lever having a coin holder and provided with an arm adapted to engage the holding rod.
- 55 11. In a machine of the class described, the combination with the poise beam, of a pivoted trip lever having a coin lever support, a spring-retracted load-actuated stud operable to tilt said lever, supplemental levers 60 engaging the trip lever, a holding rod depending from the poise beam provided with a terminal pin adapted to engage said levers and actuate the trip lever, a holding
- abutment for said locking rod, a coin chute, a coin arresting arm extending from the trip lever, a coin lever having a coin holder, a guard beyond the coin holder, a coin receptacle below the guard, and an arm on the coin lever adapted to engage the holding rod.
12. The combination with a poise beam and poise, and means connecting the beam with a weighing mechanism, of a pivoted counterweighted trip lever having a coin lever support and a coin arrester arm, of a vertically movable stud connected with the weighing mechanism adapted to support the counterweighted end of the trip lever, and a retracting spring connected with said stud.
13. The combination with a poise beam and poise, and means connecting the beam with a weighing mechanism, of a pivoted counterweighted trip lever having a coin lever support and a coin arrester arm, of a vertically movable stud connected with the weighing mechanism adapted to support the counterweighted end of the trip lever, and a retracting spring connected with said stud provided with a tension adjusting device.
14. The combination with the pivoted coin lever and holder, the trip lever having the coin lever support, and means for actuating the trip lever, of a coin chute, a coin receptacle, and a coin guard extending to a point above the coin receptacle sufficient to provide an intervening clearance space.
15. The combination with a poise beam, of a pivoted trip lever adapted to support a coin lever, a coin chute, a coin arresting arm extending from the trip lever, a coin lever having a coin holder, a tilting lever engaging the trip lever, a holding rod depending from the poise beam adapted to actuate the tilting lever, a holding abutment for said holding rod, and an element on the coin lever adapted to engage the holding rod and bind it against said bearing edge.
16. The combination with a poise beam, of a pivoted trip lever adapted to support a coin lever, a coin chute, a coin arresting arm extending from the trip lever, a coin lever having a coin holder, a pair of tilting levers engaging and each adapted to actuate the tilting lever, a holding rod depending from the poise beam having a pin adapted to engage each of said tilting levers, a holding abutment for said holding rod, and an element on the coin lever adapted to engage the holding rod and bind it against said holding abutment.
